[57] **ABSTRACT**

Disclosed is an improvement in a handle for operating an element such as a valve member, comprising a support member having a hollow portion, said support member including means to grasp a rotatable member, such as a valve control member so that movement of the support member causes rotation of the control member, said support member further including a first opening, handle means extending through said first opening into said hollow portion of said support member, said handle means including channel means therein, pawl means extending through said second opening into said hollow portion of said support member, said pawl means including pin means mounted thereto, said pin means being disposed in said channel means of said handle means whereby rotation of said handle means about its longitudinal axis causes said pin means to travel in said channel means causing the movement of said pawl means in a predetermined direction.

HANDLE FOR POSITIONING AN ELEMENT

This invention is directed to handle for positioning a control member in a plurality of predetermined positions. More particularly, this invention is directed to a handle for positioning a valve control mechanism in one of a plurality of predetermined positions.

In many instances, the positioning of a rotatable valve member is achieved by the rotation of a shaft attached to said valve member. Thus, if the shaft includes a bolt or the like rigidly mounted thereto, rotation of the shaft may be effected by rotation of the bolt. This may be readily accomplished utilizing a bolt spanner of the appropriate size.

However, many times a more accurate positioning of the valve is required. Thus, it is often desired that the valve be accurately set at one of a number of predetermined positions in order to insure proper control of the fluid flow through the valve.

Accordingly, it is an object of the present invention to provide a handle or positioning apparatus which permits the accurate positioning of the valve in one of a plurality of positions.

It is another object of the present invention to provide a handle or positioning apparatus wherein a valve may be locked in a certain position to prevent movement therefrom.

It is a further object of the present invention to provide a handle or positioning apparatus that is both extremely reliable in operation yet relatively maintenance free.

Other objects will appear hereinafter.

In accordance with the present invention, a positioning apparatus is provided wherein the twisting of a handle about its own longitudinal axis controls the motion of a pawl having a tooth at the end thereof. The tooth of the pawl may then be positioned between two adjacent teeth of a ratchet at a position to be determined by the desired position of the rotatable valve member being controlled by the handle. More particularly, the positioning apparatus of the present invention includes a handle containing a channel therein. A pin is disposed to travel in the channel. The pin is rigidly connected to a pawl so that movement of the pin in the channel causes the pawl to move in a predetermined direction. Spring means are operatively disposed with respect to the pawl in order to cause the pawl to return to its original position after the twisting force is removed from the handle. The handle is hollow and is provided with a slideable bushing therein. The slideable bushing is rigidly mounted to the pin. Thus, the moment arm imparted to the pin at one end thereof by the pawl is effectively counterbalanced by the moment arm applied to the pin at the other end thereof by the bushing. Because the angular relationship between the pin and the sides of the channel remains constant, pin travel within the channel is relatively smooth and friction-free.

Also in accordance with the present invention, the only portions of the mechanism requiring lubrication are completely enclosed in the hollow portion of the support member. Grease or other forms of lubrication are contained within the support member by a pull plug located at the bottom of the support member. Thus, there is no opportunity for dust or other foreign particles to interfere with the travel of the pin in the channel. Therefore, a smooth and reliable operation is achieved.

For the purpose of illustrating the invention, there is shown in the drawings a from which is presently preferred, it being understood, however, that the invention is not limited to the precise arrangements and instrumentalities shown.

FIG. 1 is an exploded view of the apparatus of the present invention.

FIG. 2 is an exploded view of the apparatus of the present invention showing in greater detail the mounting of the bushing and the pawl to the pin.

FIG. 3 is a top view of the apparatus of the present invention in combination with a ratchet and a valve control mechanism.

FIG. 4 is a view in elevation of the apparatus ratchet and valve control mechanism shown in FIG. 3. Referring more particularly to the drawings, the apparatus of the present invention is generally designated as 10 in FIG. 1. Support member 12 includes arm 14 extending therefrom. Arm 14 terminates in extensions 16 and 18. Indentations in arms 16 and 18 form opening 20 which has a shape complimentary to the shape of the end of the rotatable shaft rigidly attached to the valve control mechanism. Extensions 16 and 18 may be tightened about the shaft of the valve control mechanism through the use of bolt 22.

As shown in FIG. 1, the main portion of support member 12 contains a hollow interior. Access to the hollow interior may be had through aligned openings 24 and 26 or through aligned openings 28 and 30. In addition, access to the interior may be had through the bottom portion of support member 12 when pull plug 34 is removed from seal surface 32.

Handle 36 a hollow portion or sleeve 38 at the terminal portion thereof. Retention ring 42 is disposed within groove 40 on the exterior of sleeve 38. Thus, sleeve 38 may be inserted into opening 26 until retention ring 42 prevents further insertion thereof. As shown in FIG. 1, the placement of retention ring 42 and groove 40 permits sleeve 38 to be supported by openings 24 and 26 in support member 12.

Bushing 56 is slideably disposed within the hollow of sleeve 38. Thus, bushing 56 is slideably disposed with respect to channel 52 in sleeve 38. Bushing 56 further includes opening 58 in which one end of pin 50 is mounted.

Pawl 44 terminates in tooth shaped extremity 46. Pawl 44 further includes opening 48 in which the other end of pin 50 is mounted. Thus, the linear movement of pin 50 within channel 52 causes the movement of pawl 44.

Pawl 44 is supported by openings 28 and 30 in the lower portion of support member 12. Spring 54 circumscribes pawl 44 and exerts a force on pin 50. Thus, the movement of pin 50 within channel 52, which is caused by the rotation of handle 36 about its longitudinal axis, moves pawl 44 along a path parallel to the longitudinal axis of handle 36. When the rotational force on handle 36 is released, spring 54 forces pin 50 to return to the apex of channel 52 which in turn causes pawl 44 to return to its original position.

FIG. 2 shows in greater detail how the movement of pin 50 within channel 52 is controlled to achieve trouble free operation.

Sleeve 38 contains an interior surface that is smooth and relatively friction free. Bushing 56 is slideably disposed within the hollow of sleeve 38 and is com-

prised of teflon, nylon or some other relatively frictionless material. Thus, bushing 56 may slide with relative ease within sleeve 38. Bushing 56 provides support for one end of pin 50 and the other end of pin 50 is rigidly mounted in pawl 44. When pawl 44 is moved in a direction against the bias of spring 54, a force is exerted by the spring against the pawl end of pin 50. If pin 50 were not anchored in opening 58 in bushing 56, this force would cause the upper end of pin 50 to rotate about the lower end of pin 50. However bushing 56 exerts a force on the upper end of pin 50 to counterbalance the force exerted on the lower end of pin 50 by spring 54. Therefore, any tendency of the upper end of pin 50 to rotate about the lower end of pin 50 will be effectively prevented.

FIG. 3 shows a top view of the valve handle of the present invention in combination with a ratchet and the top of a valve housing. FIG. 4 is an elevation view of the subject matter shown in FIG. 3. As shown in FIGS. 3 and 4, valve shaft 88 extends through valve housing 86. Valve shaft 88 may take the form of a cylindrical shaft having a square head 64. Rotation of head 64 causes rotation of shaft 88 which in turn controls the position of the valve member such as a ball or disc.

Ratchet 60 is mounted to the top portion of valve housing 86 by screw 70 acting in conjunction with lockwasher 72 and by screw 78 acting in conjunction with lockwasher 80. In like manner, structural member 92 supporting shaft 88 is mounted to ratchet 60 by means of screw 74 acting in conjunction with lockwasher 76 and by means of screw 82 acting in conjunction with lockwasher 84.

As best shown in FIG. 3, support member 12 includes an extension 66. Extension 66 contains opening 68 at the terminal portion thereof. Opening 68 functions as a locking means. Thus, if it is desired to lock valve handle 10 in a desired position, it is only necessary to drill a hole in ratchet 60 in alignment with opening 68 when valve handle 10 is in the desired position. Relative movement between these two openings may be prevented by passing a padlock therethrough. Thus, relative movement between ratchet 60 and valve handle 10 is effectively prevented thereby prohibiting unauthorized movement of the valve.

It is also noted that valve handle 10 can be positioned so that the pawl tooth is between two adjacent teeth of ratchet 60. Thus, if a properly spaced hole is drilled in ratchet 60, extension 66 of support member 12 may be rigidly secured to ratchet 60 even though tooth 46 of pawl 44 abuts a terminal portion of one of the ratchet teeth 62 instead of being lodged between adjacent teeth.

Also, as is best shown in FIG. 3, head 64 of valve shaft 88 is grasped by extensions 16 and 18 which in turn are tightened by bolt 22 and nut 90.

The operation of the valve handle of the present invention may be best explained with reference to FIGS. 3 and 4. If it is desired to move the valve to a new position, a rotational force or twisting moment about the longitudinal axis 36. This rotation of shaft 36 causes the rotation of sleeve 38 which in turn causes pin 50 to travel in channel 52. Since pin 50 is rigidly connected to pawl 44, and since retention ring 42 prevents the movement of shaft 36 towards the valve shaft, the movement of pin 50 in channel 52 causes pawl 44 to

move in a direction away from valve shaft. This withdraws pawl 44 from its position intermediate two adjacent teeth of ratchet 60. Once pawl 44 is withdrawn, valve handle 10 may be rotated about the axis of valve shaft 88 thereby positioning the valve in a desired flow-controlling position. Since spring 54 is compressed by the movement of pawl 44 in a rearward direction, the rotational force applied about the longitudinal axis of handle 36 must be maintained while the valve handle is rotated about the axis of valve shaft 88. When the valve handle has been properly positioned the cessation of the rotational force imparted about the longitudinal axis of handle 36 causes spring 54 to expand to its non-compressed position thereby causing tooth 46 of pawl 44 to be lodged intermediate two adjacent teeth of ratchet 60.

As noted above, all elements of the valve handle requiring lubrication are located within the hollow portion of support member 12. Thus, lubrication may be effected by inserting grease or some other suitable lubricating material within the hollow portion of support member 12. After the insertion of the lubricating material, plug 34 is positioned against seal surface 32 to produce an atmospheric seal. Thus, dirt or other particles are effectively prevented from entering the hollow portion of support member 12. Therefore, all foreign materials are effectively prevented from hindering the travel of pin 50 within channel 52. Accordingly, the valve handle of the present invention is trouble free in operation and requires little maintenance.

Although there is no apparent reason why the valve handle should ever fail to operate, it is noted that, in an emergency, the valve handle could be operated without utilizing the movement of pin 50 within channel 52. Referring to FIG. 4, it is possible to pull handle 36 away from valve control mechanism 88 causing pin 50 lodged in the apex of slot 52 and to be likewise pulled away. This in turn dislodges tooth 46 of pawl 44 from between adjacent teeth of ratchet 60. Once tooth 46 is dislodged from ratchet 60, rotation of the valve handle about the axis of valve shaft 88 may be readily accomplished.

THE present invention may be embodied in other specific forms without departing from the spirit or essential attributes thereof. For example, the handle of the present invention need not be restricted to the positioning of a valve. Thus, the instant invention could be utilized to position other mechanisms positionable by the rotation of a shaft.

I claim:

1. Handle positioning apparatus comprising a support member having a hollow portion, said support member including means to grasp a rotatable member so that movement of said support member causes rotation of said rotatable member, said support member further including a first opening, handle means extending through said first opening into said hollow portion of said support member, said handle means including channel means therein and containing a hollow portion, said support member further including a second opening, pawl means extending through said second opening into said hollow portion of said support member, said pawl means including pin means mounted thereto, bushing means slidably disposed within said hollow portion of said handle means, said

pin means being disposed within said channel means of said handle means, and means mounting said pin means to said bushing means whereby rotation of said handle means about its longitudinal axis causes a movement of said channel means which in turn causes said pin means to move in said channel means thereby causing movement of said bushing means in said hollow portion of said handle means and thereby moving said pawl means in a predetermined direction.

2. Handle positioning apparatus in accordance with claim 1 wherein said bushing means is comprised of nylon or poly(tetrafluoroethylene).

3. Handle positioning apparatus comprising a support member having a hollow portion, said support member including means to grasp a rotatable member so that movement of said support member causes rotation of said rotatable member, said support member further including a first opening, handle means extending through said first opening into said hollow portion of said support member, said handle means including channel means therein, said support member further including a second opening, pawl means extending through said second opening into said hollow portion of said support member, said pawl means including pin means mounted thereto and also including biasing means associated therewith and disposed between said pin means and said support member to bias said pin means relative to said support member, said pin means being disposed within said channel means of said handle means whereby rotation of said handle means about its longitudinal axis causes a movement of said channel means which in turn causes said pin means to move in said channel means thereby moving said pawl means in a predetermined direction.

4. Handle positioning apparatus in accordance with claim 3 wherein said resilient means circumscribes said pawl means.

5. Handle positioning apparatus comprising a support member having a hollow portion, said support member including means to grasp a rotatable member so that movement of said support member causes rotation of said rotatable member, said means to grasp a rotatable member including a pair of locking arms, said arms having indentations therein in order to securely grasp said rotatable member and means for tightening

the grasp of said arms about said rotatable member, said support member further including a first opening, handle means extending through said first opening into said hollow portion of said support member, said handle means including channel means therein, said support member further including a second opening, pawl means extending through said second opening into said hollow portion of said support member, said pawl means including pin means mounted thereto, said pin means being disposed within said channel means of said handle means, whereby rotation of said handle means about its longitudinal axis causes a movement of said channel means which in turn causes said pin means to move in said channel means thereby moving said pawl means in a predetermined direction.

20 6. Handle positioning apparatus comprising a support member having a hollow portion, said support member including means to grasp a rotatable member so that movement of said support member causes rotation of said rotatable member, said support member further including a first opening, shaft means extending through said first opening into said hollow portion of said support member, said handle means including channel means therein, said support member further including a second opening, pawl means extending through said second opening into said hollow portion of said support member, said pawl means including pin means mounted thereto and including a tooth at a terminal portion thereof, said pin means being disposed within said channel means of said handle means, and ratchet means including a plurality of teeth thereon and operatively positioned relative to said pawl, said tooth of said pawl means being of such size as to fit intermediate two adjacent teeth of said ratchet means, whereby rotation of said handle means about its longitudinal axis causes a movement of said channel means which in turn causes said pin means to move in said channel means thereby moving said pawl means in a predetermined direction.

30 7. Handle positioning apparatus in accordance with claim 6, said support member further including extension means, said extension means including means to lock said extension means to said ratchet means in a predetermined position.
